UNITED STATES PATENT OFFICE

2,589,903

TUNABLE MAGNETRON OSCILLATOR

Albert L. Vitter, Jr., New Orleans, La., assignor,
by mesne assignments, to the United States of
America as represented by the Secretary of War

Application March 4, 1946, Serial No. 651,924

4 Claims. (Cl. 315—40)

1

My invention relates in general to electrical apparatus and more particularly to magnetron oscillators.

The desirability of a tunable magnetron oscillator for radio frequency generation is well known to those skilled in the art. To provide compensation for unavoidable variations in the natural output frequency of a given oscillator which may be fitted into a pre-tuned system is highly desirable. Also adjustment of a radiated frequency should be possible to adapt a transmitter to changing desired operating conditions, to cite only two examples. It is therefore advantageous to be able to tune a magnetron mechanically over a band of operating frequencies.

In some communication systems a frequency-modulated microwave signal is necessary. For this type of operation a purely mechanical means of frequency changing is unsatisfactory and a more flexible and rapid means of altering a magnetron's frequency is needed.

It is a common practice to couple an external resonant cavity to a magnetron in order to prevent excessive "pulling" of the magnetron frequency by changes in load conditions. Such devices are customarily known as stabilization cavities. In order for the stabilization cavity to have a maximal effect it should be coupled to the magnetron as tightly as possible.

In accordance with the above, it is one object of my invention to provide a tunable magnetron oscillator.

Another object is to provide a magnetron oscillator adaptable to frequency modulation.

Still another object is to provide a novel method of coupling a stabilization cavity to a vane-type magnetron.

Briefly, my invention accomplishes these and further objects which will be apparent to those skilled in the art in the following fashion: to tune the magnetron mechanically, cylindrical members electrically connected to the magnetron casing are moved in the space immediately surrounding the magnetron's straps by means of a micrometer-like screw device; a stabilization cavity of the coaxial type is coupled to the oscillator by fastening the center conductor thereof to one of the vanes of the magnetron anode; to allow for frequency modulation, a portion of the center conductor of the stabilization cavity is flared into a plate and the corresponding section of the outer conductor is thickened so that a parallel plate capacitor is formed through which a variable beam of electrons from an electron gun, for instance, may be passed to alter the capacitive ef-

2

fect and hence modulate the magnetron's frequency.

The principles and operation of my invention will be more apparent to those skilled in the art upon reference to the following specification, claims, and to the drawings, in which:

Fig. 1 represents a perspective view of a vane-type magnetron anode with an attached stabilization cavity constructed in accordance with the 10 principles of my invention;

Fig. 2 is a perspective view of the lid of the magnetron shown in Fig. 1 illustrating the details of the mechanical tuning system; and,

Fig. 3 is a sectional view of the stabilization 15 cavity showing schematically an electron gun which is utilized to perform high frequency modulation of the oscillator frequency.

Referring now to Fig. 1, there is shown a magnetron anode consisting of a ring or cylinder 5 20 within which is radially mounted, in a well known manner, a plurality of equally spaced vanes or partitions 6 which divide the interior of ring 5 into individual cavity resonators. Straps 9 and 10 are provided to effect additional separation between the various modes of oscillation which may be set up in the magnetron. The technique of strapping is well known in the art and will not be elaborated upon here.

In order to effect stabilization of the magnetron 30 output frequency under changes in load conditions and other conditions which tend to produce undesirable alteration in the magnetron operation, a stabilization cavity is connected to the magnetron. This cavity comprises a box 12, 35 along the long axis of which is positioned a central conductor 13. Box 12 is abutted against ring 5 and a hermetic seal is formed between the two members. Conductor 13 is brought through a hole 14 appreciably larger in diameter than the 40 conductor in ring 5 and brazed directly to the back of one of vanes 6. This type of connection affords exceptionally tight coupling between the magnetron and the cavity.

A portion 15 of conductor 13 is flared transversely and the wall of box 12 is built out by means of a block 16 affixed to the box wall opposite the flared portion of conductor 13.

A standard output coupling means 17 is connected to ring 5 in such a fashion as to extract 50 oscillatory energy from one of the resonant cavities between vanes 6. The bottom of ring 5 will, in practice, be sealed by a circular lid to allow evacuation of the tube. In addition, an emitting cathode will be placed in the central portion of 55 the anode ring to complete the diode structure.

For purposes of simplicity of illustration, neither a cathode nor a lid, as described, are shown in the figure.

Referring to Fig. 2, there is shown a circular plate 18, shaped to fit tightly on ring 5 and which forms part of the magnetron shell. A screw 19 passes through a threaded hole in the center of the plate 18, and at the inner extremity of the screw is attached a disc 20 to which are brazed three concentric cylinders 21, 22, and 23. The radial dimensions of these cylinders are such as to allow the cylinders, when plate 18 is placed snugly upon ring 5, to fit around and between straps 9 and 10. The screw 19 may be rotated to move the cylinders in and out of the space between straps 9 and 10. This may be done by well known micrometer means.

A possible type of electron beam generating apparatus and a suggested location therefor is shown in Fig. 3 to which reference is now made. The figure represents a section through the longitudinal axis of box 12 and conductor 13 midway between the upper and lower surfaces of the box. The electron gun shown is of a conventional type consisting of an emitting cathode 25, a control grid 26, a pierced plate 27, a focusing electrode 28, an accelerating electrode 29, and a collecting electrode 30. Appropriate voltage sources are connected between the various electrodes of the electron gun as may be necessary for operation. Between the cathode 25 and control grid 26 is connected a variable voltage source representing a modulating voltage which is used to provide the necessary variation in the density of the electron beam.

In the operation of the magnetron illustrated, oscillations are set up in a normal fashion at substantially the natural resonant frequency of the magnetron. To change the operating frequency of the magnetron to a desired value, screw 19 is turned by hand or other means to lower cylinders 21, 22, and 23 toward straps 9 and 10. As the cylinders approach and move into the spaces around and between the straps the capacitive effect between the former and the latter tends to load the magnetron and change the operating frequency of the tube in a manner which bears a relationship to the depth of penetration of the cylinder between and around the straps. At no time should there be physical contact between straps 9 and 10 and cylinders 21, 22, and 23.

The stabilization cavity is especially designed to allow for more rapid changes in frequency in the oscillator. Due to the proximity of block 16 to the flared portion 15 of conductor 13, the electric field between the members is quite strong. When the electron gun shown in Fig. 3, and which is included in box 12, directs a beam of electrons through the space between members 15 and 16, the dielectric constant of the intervening medium, normally a near-vacuum, is altered. The resonant frequency of the cavity is therefore changed accordingly. Since the cavity is tightly coupled to the magnetron, the frequency of the latter is "pulled" from its normal value. The density of the electron beam may be readily modulated and the modulation of the beam is followed by corresponding variations in the out-

put frequency of the magnetron. Frequency modulation with a swing of up to six megacycles has been accomplished by this type of electron tuning.

While there has been described what is at present considered to be a preferred embodiment of the present invention, it will be obvious to those skilled in the art that changes and modifications may be made therein without exercise of inventive ingenuity.

What I claim is:

1. A magnetron oscillator device comprising a vane-type anode electrode comprising a ring-like conducting member the interior of which is partitioned by a plurality of conducting vanes, a box of conducting material, a rod-like conducting member disposed substantially along the central longitudinal axis of said box, one portion of said rod-like conducting member being flared into a plate-like form in a plane containing said longitudinal axis, means thickening the wall of said box opposite one face of said plate-like portion of said rod-like member with the spacing between the two members substantially decreased, means joining said box to said ring-like member, and means joining one end of said rod-like member to one of said vanes whereby energy is coupled from said magnetron anode to said box.

2. A magnetron oscillator device comprising an anode electrode consisting of a ring-like member the interior of which is divided into individual cavity resonators by a plurality of vanes disposed substantially along radii of said ring-like member, an external cavity resonator having a central coaxial conductor, one of said vanes extending through said ring-like member and being integral with said conductor.

3. Apparatus in accordance with claim 2 including means connected to said cavity resonator for altering the resonant frequency thereof.

4. Apparatus in accordance with claim 3, wherein a portion of said central conductor is flared into a plate-like form within said resonator, said means for altering the frequency of said cavity resonator including an electron discharge device within said resonator for generating an electron beam longitudinally to said flared portion, and means connected to said device for controlling the electron density of said beam, said last-named means serving to alter the dielectric constant of the medium between said flared portion of said central conductor and the adjacent wall of said resonator.
